UNITED STATES PATENT OFFICE.

GARRETTSON SMITH AND HENRY BROWN, OF PHILADELPHIA, ASSIGNORS
TO ENOS S. SHANTZ AND OLIVER B. KEELEY, OF SPRINGVILLE, PA.

DESIGN FOR A RANGE-STOVE.

Specification forming part of Design No. 5,843, dated May 7, 1872.

Specification describing a Design for a Range-Stove, invented by GARRETTSON SMITH and HENRY BROWN, of the city of Philadelphia, in the State of Pennsylvania.

The nature of our design is fully represented in the accompanying photographic illustration, to which reference is made.

A represents the panel-door of the oven; B, the panel-door of the fire-chamber; and C, one of the two like side panels of the said range-stove. Each of the said panels is rectangular, and provided with a common ogee-molding, 1, modified by notched bead-work 2 along its inner edge; and from this molding the face 3 of the panel rises, in four blended plain-faced curves, toward its center, on which is a bas-relief ornamental shield or center-piece, 4. The shield on the oven-door A has on its face, in bas-relief, two ornamental Roman letters, S K, interlapping each with the other, and with the character & in bas-relief on the body of the S, thus forming a monogram. The shields on the respective panels of the fire-chamber door B and the sides C have in their centers a bas-relief eight-pointed ornament, 9, which has a flat face, divided by V-grooves into numerous pyramidal projections. D is the ash-pit door, the face 5 of which is curved in a concave manner from its upper edge down to

its bottom edge, which latter projects forward on the hearth of the range. The rotary registering-plate 6 has three sector-like openings, separated by three equal sector-like parts, 7, each of which latter are ornamented by numerous pyramidal projections produced by V-grooves between them; and the said plate rests on a flat seat produced by the raised sides 8 on the curved face of the door D. The foot E is shown (detached) in the photographic illustration, and has on the upper part of its front an ornamental shield and monogram substantially like that on the panel of the oven-door A.

What we claim as our invention is—

The design for a range-stove, consisting of the ornamented molding and shield on the panel of the oven-door A, of the fire-chamber door B, and of the sides C, as shown and described; the monogram on the oven-door and on the foot; and the curved front 5 of the ash-pit door D, in combination with the flat register-plate 6, ornamented as shown and described.

GARRETTSON SMITH.
HENRY BROWN.
